HAIR CURLER

Ernest F. Ledbetter, Chicago, Ill.

Application September 16, 1946, Serial No. 697,353

6 Claims. (Cl. 132—34)

1

This invention relates to hair curlers and has for one of its objects the production of a simple and efficient means for operating and controlling the rotation of the curling tongs in a selected direction.

A further object of this invention is the production of a simple and efficient means for facilitating the opening and closing of the curling tongs.

Another object of this invention is the production of a simple and efficient hair curler wherein the curler may be easily held in one hand and operated and controlled by the fingers of one hand of an operator, the controlling elements being conveniently located to facilitate such operation.

Other objects and advantages of this invention will appear throughout the following specification and claims.

In the drawings:

Figure 1 is a perspective view of the hair curler looking at one side thereof.

Figure 2 is a side elevational view, certain parts being shown in perspective and showing the opposite side of the curler.

Figure 3 is a horizontal sectional view taken on line 3—3 of Figure 2.

Figure 4 is a sectional view taken on line 4—4 of Figure 3.

Figure 5 is a fragmentary perspective view of the actuating gear, ratchet and operating rack and power lever.

Figure 6 is a longitudinal sectional view through the curling tong actuating mechanism.

Figure 7 is a sectional view of a modified form of the invention illustrating an electrical driving means for the curling element operating gear.

Figure 8 is a fragmentary front elevational view of the housing, the collar portion being shown in section and the latch for holding the clutch operating mechanism being shown in position.

By referring to the drawings, it will be seen that 10 designates the base which carries a standard 11 over which a sleeve 12 fits. This sleeve is preferably provided with a flared base 13 which overlies the base 10. A housing 14 is carried by the standard 11 and sleeve 12. A closure cap 15 is carried by the rear end of the housing 14. The housing 14 is provided with a front plate 16 which is secured to the housing 14 by means of screws or other suitable means 16a. A forwardly extending collar 17 is carried by the plate 16 and encases the inner end of the curling element or tongs 18. The inner end of the tongs 18 or curling element is journaled on the plate 16

2

and carries a gear 19 at its inner end within the housing 14, as shown in Figures 3 and 4. The curling element may be supported in any suitable manner to permit the curling element 18 to rotate.

A transverse actuating shaft 20 is supported upon the upright frame 21 within the housing 14 and carries at opposite ends beveled gears 22 and 23, which gears are fixed to the shaft 20. 10 This shaft 20 supports a driving gear 24 intermediate the ends thereof and this gear is loosely mounted upon the shaft 20 to freely rotate thereon. A ratchet wheel 25 is keyed to the shaft 20 to rotate with the shaft and a spring-pressed pawl, of the conventional type is carried by the driving gear 24 in a ratchet-engaging position shown in Figure 5 to rotate the ratchet 25 and shaft 20 when the gear 24 is rotated in one direction, while at the same time permitting the gear to rotate in the opposite direction without turning the ratchet wheel 25 and shaft 20.

An actuating rack bar 27 is slidably mounted longitudinally through the guiding block 28 at the bottom of the horizontally-extending housing 14, as shown in Figures 4 and 5, and engages the drive gear 24 to rotate the shaft through the pawl 26 and ratchet wheel 25 as the rack bar 27 moves inwardly. As the rack bar 27 returns to its forward position, the pawl 26 will slide over the ratchet wheel 25 and the wheel 24 may freely rotate to permit the forward return of the rack bar 27 without rotating the shaft 20.

A hand-operated lever 29 is pivoted, as at 30, to the lower end of the standard 11 and engages 35 the slotted depending finger 31 carried by the forward end of the rack bar 27. A spring 32 is also secured at one end near the lower end of the standard 11, and the opposite end of the spring 32 fits in the guide 34 of the lever 29 to return the lever 29 to its forward position when it is released, it should be understood that the rack bar 27 is moved inwardly by the operator who holds the device in his hand, as shown in dotted lines in Figure 2, and extends his fingers 40 around the lever 29. By squeezing the lever 29 the rack bar 27 will be forced rearwardly, thereby driving the gear 24 and rotating the shaft 20 which will consequently rotate the curling element 18 in the manner hereinafter described. As soon as pressure is released on the lever 29, the spring 32 will return the lever 29 and rack bar 27 to its forward position.

The shaft 20, is slidably mounted through its support 21, and is shiftable longitudinally to permit the gears 22 and 23 to be selectively moved

into and out of engagement with the bevelled gear 19 at opposite sides thereof to control the direction of rotation of the curling element 18, which is secured to the gear 19. A clutch operating lever 35 is pivoted within the housing 14 to a horizontal shaft located in the bottom of the housing 14. This shaft 36 carries a clutch arm 37 at the opposite end thereof, which clutch arm 37 engages the clutch collar 38 of the gear 22. A finger-piece 39 is secured to the operating lever 35 and is located outside of the housing 14 where it may be engaged by the thumb or finger of an operator to swing the lever 35 and the clutch arm 37 to shift the shaft 20 and gears 22 and 23 laterally. By swinging the operating lever 35 upwardly, the gear 22 will be moved to a position to mesh with the gear 19 and move the gear 23 to a disengaging position. By swinging the lever 35 downwardly, the gear 23 will be moved to a meshing position with the gear 19 and the gear 22 will be moved to a disengaging position. A spring-pressed latch 40 is carried by the plate 16 and engages the finger-piece 39 to hold the clutch in a set position.

A curling tong control sleeve 41 is slidably mounted within the collar 17. This sleeve is provided with an inturned flange 42 which engages an actuating spring finger 43 of the pivoted spring-pressed jaw 18^a of the curling element or tong 18, to open the tongs. As the sleeve 41 is moved inwardly, the spring finger 43 will automatically open the jaw 18^a. An operating trigger yoke 44 is pivoted to a bracket 45 carried by the collar 17. This trigger yoke 44 is connected to the sleeve 41 by means of screws 46 which pass through slots 47 formed in the collar 17. The yoke 44 is provided with a depending finger-engaging portion 48 which extends below the housing 14 to a position where it may be easily reached for operation by a finger of the operator. The sleeve 41 may be shifted rearwardly by means of the trigger yoke 44 to open the tongs 18 and a suitable spring 44^a is preferably provided to return the yoke 44 to its normal position to close the tongs, the spring 43^a of the tongs or curling element assisting in this operation.

From the foregoing description it should be noted that the instrument is held in one hand of the operator and by squeezing the lever 29, the rack bar 27 will be forced inwardly to rotate the gear 19 and the curling element 18, the direction of rotation being controlled by shifting the gears 22 and 23 selectively into mesh with the gear 19 by operating the finger piece 39 and clutch arm 37. When the lever 29 is released the parts will return to their normal position, the gear 24 being loosely mounted, permitting this operation. The jam 18^a of the tongs 18 may be opened by pressing the finger upon the finger-engaging portion 48 of the yoke 44. All parts are so located as to permit the device to be held in one hand and operated and also to conveniently control the direction of rotation of the curling element as well as the opening of the curling element by the fingers of the hand holding the device.

In the form shown in Figure 7, the housing 14^a carries a transverse shaft 50 upon which a motor 51 is mounted for driving the same. Shiftable gears 52 and 53 controlled by a clutch shifting means 54 are also carried by the shaft 50. A clutch lever 55 engages the clutch shifting means 54 and is pivoted, as at 56, to the casing 14^a. The lever 55 may extend downwardly of the housing 14^a where it may be conveniently operated by the fingers of an operator. A switch

57 is conveniently located relative to the lever 55 upon the housing 14^a to turn the motor 51 on and off. The remaining portions of the device are constructed as illustrated and described relative to Figures 1 to 6 inclusive. The only difference in this form shown in Figure 7 over the form shown in Figures 1 to 6 is the electrical driving means and associated parts.

It should be understood that certain changes in detail construction may be made without departing from the spirit of the invention so long as these changes fall within the scope of the claims hereto attached. It should be further understood that although I have disclosed a novel operating means mechanically operated, the electrical or motor driven operating means may be used without departing from the spirit of the invention.

It should be further understood that the tongs 18 may be electrically or otherwise heated in the conventional manner, without departing from the spirit of the invention.

What is claimed is:

1. A hair curler of the class described comprising a housing, a substantially right-angularly extending standard supporting said housing and constituting a hand-grip, an opening and closing curling element carried by said housing and protruding beyond the housing at substantially right angles to the hand-grip, a driving mechanism within said housing for driving said curling element, a finger engaging actuating lever extending longitudinally of said hand-grip and operably connected to the driving mechanism for driving said mechanism, and said actuating lever being pivoted to the standard and being movable toward the standard by a squeezing action of the hand of an operator.

2. A hair curler of the class described comprising a housing, a substantially right-angularly extending standard supporting said housing and constituting a hand-grip, an opening and closing curling element carried by said housing and protruding beyond the housing at substantially right angles to the hand-grip, a driving mechanism within said housing for driving said curling element, a finger engaging actuating lever extending longitudinally of said hand-grip and operably connected to the driving mechanism for driving said mechanism, said actuating lever being pivoted to the standard and being movable toward the standard by a squeezing action of the hand of an operator, and a flat supporting base for said standard for supporting said standard in an upright position and thereby holding the curling element out of contact with other objects when said base is placed upon a support.

3. A hair curler of the class described comprising a housing, a substantially right-angularly extending standard supporting said housing and constituting a hand-grip, an opening and closing curling element carried by said housing and protruding beyond the housing at substantially right angles to the hand-grip, a driving mechanism within said housing for driving said curling element, said curling element having an angularly extending actuating finger, a sleeve carried by said housing and movable longitudinally relative to the curling element and having means engaging said finger for automatically opening said curling element as said sleeve is moved in one direction relative to the curling element, a trigger pivoted to said housing and connected to said sleeve for moving said sleeve longitudinally relative to said curling element,

and said trigger being located adjacent said standard and away from the curling element to protect the hand of an operator from accidentally contacting the curling element should the curling element be heated.

4. A hair curler of the class described comprising a housing, a substantially right-angularly extending standard supporting said housing and constituting a hand-grip, an opening and closing curling element carried by said housing and protruding beyond the housing at substantially right angles to the hand-grip, a driving mechanism within said housing for driving said curling element, said curling element having an angularly extending actuating finger, a 10 slideable sleeve carried by said housing and movable longitudinally relative to the curling element and having means engaging said finger for automatically opening said curling element as said sleeve is moved in one direction relative to the curling element, a trigger pivoted to said housing and connected to said sleeve for moving said longitudinally relative to said curling element, and said sleeve trigger being located adjacent said standard and away from the curling 15 element to protect the hand of an operator from accidentally contacting the curling element should the curling element be heated.

5. A hair curler of the class described comprising a housing, a driving mechanism, a curling element driven by said driving mechanism, a standard extending at substantially right angles to the housing and constituting a hand-grip, a hand operated lever pivoted to said standard, a 20 reciprocating rack bar slideable longitudinally of the housing for actuating said driving mechanism, a slotted depending finger carried by the rack bar and slidably engaging said lever, said lever being adapted to actuate said rack bar as said lever is swung in one direction relative to the standard by a squeezing action of the hand of an operator, and a spring return for said lever.

nism, a slotted depending finger carried by the rack bar and slidably engaging said lever, and said lever being adapted to actuate said rack bar as said lever is swung relative to the standard by a squeezing action of the hand of an operator.

6. A hair curler of the class described comprising a housing, a driving mechanism, a curling element driven by said driving mechanism, a standard extending at substantially right angles to the housing and constituting a hand-grip, a hand operated lever pivoted to said standard, a reciprocating rack bar slideable longitudinally of the housing for actuating said driving mechanism, a slotted depending finger carried by the rack bar and slidably engaging said lever, said lever being adapted to actuate said rack bar as said lever is swung in one direction relative to the standard by a squeezing action of the hand of an operator, and a spring return for said lever.

ERNEST F. LEDBETTER.
